UNITED STATES PATENT OFFICE.

JOHN L. CLAUDIN, OF MORTON, ILLINOIS, ASSIGNOR, BY MESNE ASSIGNMENTS, TO INTERLOCKING FENCE COMPANY, OF MORTON, ILLINOIS, A CORPORATION OF ILLINOIS.

WIRE-FENCE FABRIC.

SPECIFICATION forming part of Letters Patent No. 739,798, dated September 22, 1903.

Application filed September 9, 1902. Serial No. 122,686. (No model.)

To all whom it may concern:

Be it known that I, JOHN L. CLAUDIN, a citizen of the United States, residing at Morton, in the county of Tazewell and State of Illinois, have invented certain new and useful Improvements in Wire-Fence Fabrics; and I do hereby declare that the following is a full, clear, and exact description of the invention, which will enable others skilled in the art to which it appertains to make and use the same.

This invention has reference to a wire-fence fabric and to that type of fence wherein the meshes are of hexagonal form, and the application herein is an improvement upon that fabric shown in my application bearing Serial No. 86,269, and I have incorporated in this case the structure therein shown for the purpose of illustration only.

The invention has for its further object to provide one or more body-wires or intermediate strands through the body of the fabric which are interlocked throughout their length with adjacent mesh-wires of the fabric, which are themselves interlocked and which form the hexagonal mesh. The said strands where they are employed in the fabric pass through each hexagonal mesh and are interlocked with the wires forming said mesh at the points of interlocking thereof.

It is further provided to interlock the adjacent wires forming each mesh which lie in the same vertical plane, first, with a right and left hand twist, and next with a left and right hand twist—that is, the adjacent mesh-wires of the fabric throughout its height and length are interlocked; first, right and left, and then left and right, and so on throughout the length of the fabric.

That my invention may be more fully understood reference is had to the accompanying drawings, forming a part of this specification, in which—

Figure 1 is a view showing a strip of fencing in outline embodying my improvement where-
in the selvage-strands are cable-wires and with a horizontal strand-wire shown extending through the central body of the fence. Fig. 2 is a figure showing a strip of fencing in outline embodying my improvement where-

in the selvage-strands are single wires and with two longitudinal or horizontal strand-wires which are interlocked with the mesh-wires at each side. Fig. 3 is a view showing a strip of fencing in outline embodying my improvement wherein the selvage-strands are single wires and showing horizontal or longitudinal strand-wires extending across each hexagonal mesh and interlocked with the adjacent interlocked mesh-wires. Fig. 4 is an enlarged detail showing the manner of interlocking two wires as they appear in elevation. Fig. 5 is a plan of Fig. 4. Fig. 6 is an enlarged detail showing the manner of interlocking two mesh-wires and an intermediate strand-wire as they appear in elevation. Fig. 7 is a plan of Fig. 6. Fig. 8 is an enlarged detail showing the manner of interlocking two mesh-wires and an intermediate strand-wire as they appear in the fabric and opposite to the interlock of the wires shown in Fig. 6. Fig. 9 is an enlarged detail showing the manner of interlocking adjacent mesh-wires of the fabric with the selvage-strands thereof when the selvage is a cable.

The figures may be better understood from the following: Fig. 4 is a detail of the fabric as the same would appear in the block surrounded by the dotted lines *a a* of Fig. 2, or as it would appear in the block surrounded by the dotted lines *b b* of Fig. 2, dotted lines being added to Fig. 4 for the purpose of illustrating the direction in which the lines would appear if taken from that portion of the fabric bounded by the dotted lines *b b*, as suggested. Fig. 6 is a detail of the fabric as the same would appear in the block surrounded by the dotted lines *c c* of Fig. 3. Fig. 8 is a detail of the fabric as the same would appear in the block surrounded by the dotted lines *d d*, of Fig. 3, which illustrates the alternate form of interlocking adjacent mesh-wires with a strand of the fabric. Fig. 9 is a detail of the fabric as the same would appear in the block surrounded by the dotted lines *e e* of Fig. 1.

I have shown from a description of the figures that the selvage-strands of the fabric may be single wires or a cable, and in the figures, 1 indicates the upper selvage-strand, and 100

2 the lower selvage-strand, of a fabric. The mesh-wires are indicated as 3 and 4, which at intervals throughout the length of the fabric are interlocked with each other at 5, and the 5 mesh-wires adjacent to the selvage-strands are interlocked at intervals therewith, as at 6.

The manner of forming the hexagonal mesh herein illustrated is known to the trade, and it is not necessary to go into detail herein, 10 and while the form of mesh—that is, a hexagonal mesh—is old I believe it is new to interlock the wires and to form a fabric such as I illustrate and describe.

7 indicates a horizontal strand-wire extended longitudinally through the fabric, and at points of interlocking; 5, of the mesh-wires with each other the wire 7 is interlocked therewith. These wires may be placed as shown in Figs. 1, 2, or 3, or at any point intermediate the selvage-strands, as may be desired, and it is here that I want to call particular attention to the manner of interlocking the mesh-wires with the adjacent mesh-wires upon one side thereof and then with the other. 20 25 For instance, the interlocking of the wires through the line $x\ x$ of Fig. 3, we will say, is right and left and the next succeeding interlocking of the wires through the line $y\ y$ is left and right, or just opposite to the previous 30 lock, according to which side of the fence you are examining.

Referring to Fig. 4, which for the purpose of illustration may be taken as an interlock of the selvage-strands of one wire with the 3; adjacent mesh-wire thereto of the fabric, or in dotted lines as an interlock of adjacent mesh-wires 3 and 4 in the body of the fabric. On this view, as well as in Fig. 5, I have placed the numerals 3 and 4 upon the wires 40 throughout the interlocking thereof to show their relation.

Fig. 6 is a detail of the wires 3 and 4 and the intermediate strand-wires 7, all three of which are interlocked together, and the wires 45 throughout their interlocking are designated by their proper numerals to show their relation, and the wires 7 are provided with the slightly-curved portions 8 adjacent to the point of interlocking with the mesh-wires for 50 the purpose of allowing sufficient contraction and expansion of the body of the fabric during extreme hot or cold weather.

In Fig. 8 is shown a detail of that part of the fabric composed of wires 3, 4, and 7, interlocked just opposite to that shown in Fig. 6, Fig. 6 showing the wires interlocked as they would appear in the fabric through the lines $x\ x$, Fig. 3, and Fig. 8 showing the wires interlocked as they would appear in the fabric 60 through the lines $y\ y$. In Fig. 6 the wires 3 appear going under and the wires 4 going over, with the wires 7 entering between the same, and in Fig. 8 the wires appear just opposite, the wire 3 going over and the wire 4 going under, with the wire 7 entering between the same and just opposite to that shown in Fig. 6.

In Fig. 9 the selvage-strands are here shown as a cable with the wires next thereto interlocked therewith. When interlocking what 70 is known as a "cable" selvage-strand with an adjacent mesh-wire of the fabric, the wires are fed and gripped similar to the manner in which the wires 3, 4, and 7 are fed and gripped with the exception that as the three 75 wires (two of which form the cable and the other forming one of the mesh-wires of the body of the fabric) are interlocked and at the point of finishing of such interlocking the wires which are to form the cable are twisted 80 together in the form of an ordinary twist—that is, a twist running in one direction only and continued to a point where it is again desired to interlock the mesh-wires of the fabric next thereto therewith when the cable-twisting devices are stopped and the interlocking devices brought into play.

I am aware that patents have been granted for a wire-netting formed from continuous wires interlocked at intervals by twists which 90 severally comprise, first, a right-hand twist, and then a left-hand twist; also, that this same form of netting has been made where selvage-wires have been connected with outer wires of the fabric passed bodily around the 95 selvage-wires; also, that where the continuous wires have been connected with a right-and-left turn to the nearest wire on each side that an eye has been left in the center where the interlocking of the mesh-wires is made 100 through which a horizontal or vertical wire is carried together therewith forming a part of the fabric. I am also aware that it is not new to interlock continuous and adjacent 105 mesh-wires where there is provided an intermediate plain portion between the points of interlocking. I am further aware that it is not new to provide a fabric with meshes having substantially the same form as mine, but wherein the twists have been in but one direction only; but in my fabric special stress 110 is laid upon the right-and-left twists at intervals the width of the fabric on lines $x\ x$ and the left-and-right twists on lines $y\ y$ of Fig. 3. Special stress is also laid upon the fact 115 that the intermediate and horizontal mesh-wires are interlocked with the wires 3 and 4 and that the last-mentioned wires are not connected with the horizontal wires either by being passed bodily around the same or the 120 horizontal wires carried through eyelets formed by or during the interlocking, and attention is again called to the selvage-strands comprising a cable the wires of which are interlocked during the period of forming the 125 cable with the wires of the fabric next thereto.

In the drawings is illustrated a wire fabric having a graduated mesh; but I do not wish to limit myself to such a showing, as it may be desirable to make this fabric with a uniform mesh, nor do I wish to limit myself to any specified number of horizontal strand-wires intermediate the selvage-strands. It is to be noted, however, that the employment

of the strand-wire 7 strengthens the body of the fabric and where employed, as in Fig. 2, acts as double cable or selvage wire.

Having thus fully described my invention, what I claim, and desire to secure by Letters

5 Patent of the United States, is—

In a wire-fence fabric, the combination of a series of body-wires which are intertwined between the meshes by reverse twists alternately from right to left and left to right, of 10 selvage-strands composed of two wires intertwined at intervals with adjacent top and bottom body-wires of the fabric by reverse

twists to form cable selvage-strands, and horizontal strand-wires extending through the 15 meshes of the fabric and intertwined with the body-wires at the point of intersection therewith, substantially in the manner and for the purposes described.

In testimony whereof I affix my signature 20 in presence of two witnesses.

JOHN L. CLAUDIN.
